INKSTAND

Emitt L. Pike, Winston-Salem, N. C.

Application May 1, 1939, Serial No. 271,135

7 Claims. (Cl. 120—59)

This invention relates to inkstands, and its general object is to provide an inkstand of the fountain type, in which the level of ink in the well can be readily changed and maintained at any desired height, regardless of the quantity of the ink in the reservoir, or source of supply, and that feature makes it possible to use pen points of any desired length, from the shortest stub type to the longest ball type, so that the proper quantity of ink can be had upon the pen point, without fear of dipping the same to a depth beyond its connection with its holder, and obtaining ink upon the latter, therefore the holder as well as the fingers of the user will be retained free from ink, as will be apparent.

A further object is to provide an inkstand constructed for fittingly receiving an ink bottle of the type now in general use, so that a bottle in which the ink is purchased, can be used with my stand to provide the reservoir therefor, as distinguished from a special type of reservoir within which the ink must be poured from a bottle.

Another object is to provide an inkstand that includes guiding and supporting means for the pen and one or more of such means may be provided to accommodate an equal number of pens.

A further object is to provide an inkstand of the character set forth, that is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a front view of one form of my inkstand, with parts broken away and in section.

Figure 2 is a side view thereof.

Figure 3 is a view partly in section, taken through a modified form of stand.

Figure 4 is a sectional view taken approximately on line 4—4 of Figure 3, looking in the direction of the arrow.

Referring to the drawing in detail, and particularly to the form as shown in Figures 1 and 2, the reference numeral 1 indicates the body that provides a well for receiving the ink, and the body of this form is preferably of circular forma-

tion, as shown, in that it includes an annular vertical wall and disk like bottom and top walls 2 and 3, the top wall being shown as integral with the vertical wall, but it may be in the form of a cover detachably associated therewith. Formed on and rising from the top wall and preferably at an inclination is a pair of pen guides 4 opening into the well and these guides may be restricted at their juncture with the top wall, as well as provided with outwardly flared upper ends, to facilitate the application of the pens therein, as will be apparent.

The bottom wall has formed thereon and rising centrally therefrom, a hollow cylindrical member 5, that is interiorly threaded and may be of a height to extend above the top wall, with the latter having an opening therein for receiving the member 7, as shown. The member 5 is provided with an opening 6 extending vertically therein from its lower end and which provides an outlet for the passage of the ink from the member 5 into the well of the body, as will be apparent upon inspection of Figure 1.

The valve member of my stand includes a housing 7 provided with an annular depending skirt 8 exteriorly threaded and of a diameter to fit within the cylindrical member 5 for threaded association therewith and for vertical movement of the valve member for a purpose which will be later described.

The housing is restricted or tapered inwardly from the skirt 8 and has formed in the upper end thereof a conical seat 9 for receiving a like shaped head 10 of a plunger valve which includes a stem 11 formed on the head and of a length to extend a considerable distance below the skirt 8 for engagement with the bottom wall 2 for moving the valve to open position against the action of a coil spring 12 that is sleeved on the stem, with its end convolutions engaging the bottom portion of the seat 9 and a washer like disk 13 mounted upon an abutment pin 14 extending transversely through the stem. The stem is provided with a guide member 15 secured to and extending diametrically of the skirt.

Formed on the upper end of the housing 7 is a cup-like member 16 providing a cap, in that it includes an annular threaded portion for threadedly receiving the neck 17 of a bottle 18 which provides the ink reservoir for my stand, and mounted in the cup-like member 16 is a gasket 19 to provide a leak proof connection between the neck and the cup-like member, as will be apparent upon inspection of Figure 1. By that construction, it will be obvious that the ink reser-

voir of my stand is in fact a bottle of the type now generally used and can be purchased filled with ink at any stationary store or the like. However, any type of container providing a reservoir may be used with my stand, providing of course the container includes a threaded neck which will fit the cup-like member.

From the foregoing description and disclosure in the drawing, it is believed that the operation will be clear, but it might be mentioned that the valve member is threaded on the neck of the bottle, thence the valve member and bottle are inverted to the position shown and threaded into the cylindrical member 5, until the valve stem engages the bottom wall 2, for disposing the valve into open position. The ink then flows by gravity from the bottle into the cylindrical member 5 and from the latter into the well. The greatest height of the level of the ink within the well will of course be even with the upper end of the opening 6, but the depth of the ink below that level can be varied merely by threading the valve member so that the skirt will extend below the upper end of the opening 6, therefore it will be seen that any desired level may be maintained within the well, to accommodate pen points of various lengths and types, as and for the purpose as previously set forth.

In the modified form of Figures 3 and 4, the body 20 is preferably square or of rectangular formation, but likewise provides a well for the ink having a hollow cylindrical member 21 secured to and rising from the bottom wall adjacent a marginal edge thereof for threadedly receiving the skirt of a valve member which is identical to that of the form of Figures 1 and 2, therefore the same reference numerals are applied to the parts thereof, as well as to the cup-like member which provides a cap for the bottle. However, in the form of Figure 3 I provide ink displacement means, to cooperate with the skirt and outlet opening of the hollow cylindrical member 21 to change the depth of the ink within the well, and for that purpose the body 20 has a partition 22 disposed therein to provide a chamber 23 within which is arranged a block 24 having secured thereto and rising therefrom a threaded shank 25 extending through a reinforced opening in the cover plate 26 and threaded on the outer end of the shank 25 is a nut 27 provided with a serrated flange 28, so that upon threading the nut on the shank, the block will be raised or lowered within its chamber, which will result in changing the height of the ink level within the well. The partition 23 is provided with an opening 29 for passage of the ink into and out of the chamber, as will be apparent.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A fountain inkstand comprising a body providing a well, a reservoir for supplying ink to the well, valve means having the reservoir detachably connected thereto and including a normally closed valve, hollow supporting means for said valve means and secured within the well, said supporting means having said valve means movably mounted therein for engagement of said valve with the bottom of the well to open said

valve, and said supporting means having an outlet opening controlled by said valve means to vary the depth of the ink within the well.

2. A fountain inkstand comprising a body providing a well, a reservoir for supplying ink to the well, valve means having the reservoir detachably connected thereto and including a normally closed valve, hollow supporting means for said valve means and secured within the well, said supporting means having said valve means movably mounted therein for engagement of said valve with the bottom of the well to open said valve, and ink displacement means to vary the depth of the ink within the well.

3. A fountain inkstand comprising a body providing a well, a reservoir for supplying ink to the well, valve means having the reservoir detachably connected thereto and including a normally closed valve, hollow supporting means for said valve means and secured within the well, said supporting means having said valve means movably mounted therein for engagement of said valve means with the bottom of the well to open said valve, said supporting means having an outlet opening controlled by said valve means, and ink displacement means for operating the valve means to vary the depth of the ink within the well.

4. A fountain inkstand comprising a body providing a well, a reservoir for supplying ink to the well, valve means having the reservoir detachably connected thereto and including a housing, a normally closed valve within said housing and the latter including a depending skirt, hollow supporting means having the skirt threadedly mounted therein for engagement of said valve with the bottom of the well to open said valve and said supporting means having an outlet opening controlled by the skirt to vary the depth of the ink within the well.

5. A fountain inkstand comprising a body providing a well, a reservoir in the form of a bottle for supplying ink to the well, valve means including a housing, a cup-like member formed on and rising from the housing and having the reservoir detachably connected thereto, a normally closed spring pressed valve within said housing and including a stem, a threaded skirt depending from said housing, hollow cylindrical means secured to and rising from the bottom of the well and having an outlet opening therein, said hollow cylindrical means threadedly receiving the skirt for movement of the valve means for engagement of the stem with the bottom of the well to open said valve and for the skirt to control said outlet opening to vary the depth of the ink within the well, and pen receiving means rising from the body and communicating with the well.

6. A fountain inkstand comprising a body providing a well, a reservoir in the form of a bottle for supplying ink to the well, valve means including a housing provided with an intermediate restricted portion having a seat at the upper end thereof, a cup-like member formed on and rising from the housing and having the reservoir detachably connected thereto, a normally closed spring pressed valve including a head engageable with the seat, a stem depending from the head, a threaded skirt depending from the restricted portion and having the stem extending therethrough, a hollow cylindrical member secured to and rising from the bottom of the well and having an outlet opening therein, said hollow cylindrical member threadedly receiving the skirt for movement of the valve means for engagement of the

stem with the bottom of the well for opening said valve and for the skirt to control said outlet opening, ink displacement means cooperating with the skirt and outlet opening to vary the depth of the ink within the well and pen receiving means rising from the body and communicating with the well.

5. 7. A fountain inkstand comprising a body providing a well, a reservoir for supplying ink to the well, valve means having the reservoir detachably connected thereto and including a normally closed valve, hollow supporting means for said valve means and secured within the well, said supporting means having said valve means mov-

ably mounted therein for engagement of said valve with the bottom of the well to open said valve, said supporting means having an outlet opening controlled by said valve means, a partition within the well and having an opening therein, said partition providing a chamber, a block movable vertically within the chamber and cooperating with the valve means to vary the depth of the ink within the well, means for raising and lowering said block, and pen receiving means rising from the body at an inclination with respect thereto and communicating with the well.

10. EMIT L. PIKE.
